UNITED STATES PATENT OFFICE.

GILBERT E. FERRY, OF OMAHA, NEBRASKA.

ANGLE-BRACE FOR SCREEN-FRAMES.

933,067.

Specification of Letters Patent. Patented Sept. 7, 1909.

Application filed December 2, 1908. Serial No. 465,651.

To all whom it may concern:

Be it known that I, GILBERT E. FERRY, a citizen of the United States, residing at Omaha, in the county of Douglas and State of Nebraska, have invented certain new and useful Improvements in Angle-Braces for Screen-Frames, of which the following is a specification.

This invention relates to improvements in angle braces for screen frames, and has for its object the provision of a brace which may be conveniently constructed and may be manufactured without waste of material.

Another object is the provision of an article of this class which may be used for bracing the corners and also the cross strip of a screen-frame.

The material used is preferably sheet metal, as it is comparatively inexpensive, and has an adequate strength since it is an integral structure, and, by reason of the transverse disposition of the several parts, the walls coöperate to reinforce each other.

With these and other objects in view the invention consists of the novel combination and arrangement of parts as described herein, pointed out by the claims, and as illustrated in the drawing, wherein,—

Figure 1 is a plan view of a metal sheet or plate used for making a single brace, the incised and bent parts being indicated, respectively, by solid and broken lines. Figs. 2 and 3 are perspective views of an angle brace embodying my invention. Figs. 4 and 5 are perspective views showing these braces mounted upon the horizontal end-strip and vertical side-strips of a screen frame. Figs. 6 and 7 are perspective views somewhat similar to Figs. 2 and 3, and showing the end-extensions of the brace bent to occupy the same plane as the sides, and used as a brace upon the cross strip and vertical strip of a screen frame. Figs. 8 and 9 are perspective views illustrating operative mounting of the braces last named. Fig. 10 is a side view of a screen frame, showing the braces mounted upon the vertical side-strips, and horizontal cross strip and end-strips thereof.

Referring now to the drawing for a more particular description, numeral 1 indicates a plate or sheet of metal employed to form angle brace 2, and for this purpose this sheet is incised on line *a a* and upon transverse line *b b*, and thereafter bent substantially 90 degrees upon adjacent lines, parallel with

line *a a*, indicated at *c c*, *d d*, to form a rectangular back 3 with a terminal 27, and with adjacent, integral, parallel sides 4 and to form end-portions 5 with oppositely-disposed, transverse extensions, wings or flanges 6, each of sides 4 having an angular incision *e f g* intermediate its ends and opening upon its side edge and bent on line *e h* to form the extensions or wings 7 of end-portions 5, with transverse adjacent flanges 8 thereon. Sides 4 are also bent transversely upon longitudinal lines *f i*, to form thereon the pair of longitudinal flanges 19.

The angle brace as described is an integral structure, and in use, after terminal 9 of horizontal end-strip 10 has been seated near the terminal and adjacent the inner face 11 of vertical side-strip 12, as shown in Fig. 10, back 3 may be seated inclosingly upon the outer face 13 of said end-strip, extensions 6 occupying the same plane as the back and being seated upon terminal 14 of vertical strip 12, and may be secured by use of suitable pins or nails in openings 15, and sides 4 will have seatings upon the outer and inner sides of said horizontal strip, secured by nails in openings 16; and ends 5 with extensions 7 will have seatings upon opposite sides 17 of strip 12, flanges 8 being seated upon the inner side of this strip and held by nails within openings 18, flanges 19 being seated upon the inner side 25 of horizontal end-strip 10, and held by nails or pins in openings 20.

The angle brace thus described may be constructed very economically, and operates as an effective holding means for use upon corners of the screen frame.

To illustrate economy of material in manufacture and convenience in use, angle brace 21 is shown in Figs. 6, 7, 8 and 9. This angle brace is the same as already described, except that extensions 6, above mentioned are bent outward 90 degrees to provide arms or flanges 6' disposed upon the same plane as sides 4', and when thus bent, back 3' may be disposed upon the upper face 22 of horizontal cross piece 24, with its outer terminal 27 in engagement with the inner face 11 of strip 12, and sides 4' may be seated upon the outer sides 23 of said cross piece and secured thereon by nails passed within openings 16', flanges 19' having seatings upon the lower face 26 of cross-piece 24, and flanges 19' may be secured by use of pins or

nails passed within openings 20'; and ends 5' and extensions 7' thereof will have seatings upon sides 17 of strip 12, flanges 8' thereof having seatings upon the inner side 5 of this strip secured by nails or like members within openings 18'. As thus constructed and mounted the device provides a holding means for the cross piece upon the vertical strip, convenient in use and effective 10 in operation, and when securing together the several strips shown in Fig. 10, braces 2 and 21 may be used interchangeably by raising or lowering flanges 6 or 6' to the positions described, as required, for securing together 15 the corners, or to secure an intermediate cross-strip upon the vertical strips of the frame. It will be noted that the metal plates or sheets 1 may be of the same size and shape, and are incised the same, for the 20 formation of either of the herein described angle braces.

Having fully described my invention, what I claim as new and desire to secure by Letters Patent, is,—

25 1. The combination with the vertical and horizontal strips of the frame, of an L-shaped brace therefor, comprising a back engaging the outer face of the horizontal strip; parallel sides formed integral with the back 30 for seatings upon the sides and having longitudinal edges turned in directions toward each other for seatings upon the inner face of said horizontal strip; end-portions integral with the sides, each having oppositely-disposed wings integrally formed thereon; one of the wings of each end-portion disposed adjacent the outer terminal of and upon the plane of said back, the opposite wings of said end-portions disposed 35 engagingly upon the sides of the vertical strip, each having an integral flange turned in directions toward each other for seatings upon the inner face of said vertical strip.

40 2. The combination with the vertical and horizontal strips of the frame, of an L-shaped brace therefor, comprising a back engaging the outer face of the horizontal strip; parallel sides formed integral with the back 45 for seatings upon the sides of the horizontal strip; end-portions integral with the sides, each having oppositely-disposed wings integrally formed thereon; one of the wings of each end-portion disposed adjacent the outer terminal of and upon the plane of said back, the opposite wings of said end-portions seated upon the sides of the vertical strip; means to secure the sides upon the horizontal strip and means to secure the end-portions upon said vertical strip.

45 3. An L-shaped angle brace of sheet metal, comprising, in combination with the vertical and horizontal strips of the frame, a rectangular back for engagement with the outer face of the horizontal strip; parallel side 50 portions formed integral with the back for

seatings upon the sides of said horizontal strip, each of the side portions extended longitudinally and outwardly of the back to form an end portion with integral, transverse holding-wings thereon, said end portions and transverse holding wings adapted to have seatings upon the sides of said vertical strip. 70

4. An L-shaped angle brace of sheet metal, comprising, in combination with the vertical and horizontal strips of the frame, a rectangular back engaging the outer face of the horizontal strip; parallel side portions formed integral with the back for seatings upon the sides and having longitudinal edges disposed in opposed relation for seatings upon the inner face of said horizontal strip, each of the side portions extended longitudinally and outwardly of the back to form an end portion with integral, transverse holding-wings thereon, said end portions and transverse holding wings adapted to have seatings upon the sides of the vertical strip. 80

5. An L-shaped angle brace of sheet metal, comprising, in combination with the vertical and horizontal strips of the frame, a rectangular back engaging the outer face of the horizontal strip; parallel side portions formed integral with the back for seatings upon the sides of the horizontal strip, each of the side portions extended longitudinally and outwardly of the back to form an end portion with integral, transverse, flange-bearing holding-wings thereon, said end portions and transverse holding-wings adapted to have seatings upon the sides with said flanges engaging the inner face of said vertical strip. 90

6. A T-shaped brace of sheet metal, comprising, in combination with the horizontal cross-strip and vertical strip of the frame, a rectangular back adapted to have a seating upon one of the horizontal faces of the horizontal strip, parallel side portions integral with the back to be seated upon the vertical faces of the horizontal strip, each of the side portions extended longitudinally and outwardly of the back to form end-portions with transverse, vertical, oppositely-disposed wings, said end-portions and wings adapted to engage the sides of said vertical strip. 105

7. A T-shaped brace of sheet metal, comprising, in combination with the horizontal cross-strip and vertical strip of the frame, a rectangular back adapted to have a seating upon one of the horizontal faces of the horizontal strip, parallel side portions integral with the back adapted to have seatings upon the vertical faces and having integral longitudinal flanges for seatings upon the opposite horizontal face of the horizontal strip; each of the side portions extended longitudinally and outwardly of the back to form end-portions with transverse, oppositely-dis- 110 115 120 125 130

posed wings, said end-portions and wings adapted to engage the sides of said vertical strip.

8. In combination, a T-shaped brace of sheet metal, comprising, a frame having a vertical strip and a horizontal strip, a rectangular back adapted to have a seating upon one of the horizontal faces of the horizontal strip, parallel sides integral with the back 10 adapted to have seatings upon the sides of the horizontal strip, each of the sides extended longitudinally and outwardly of the back to form end-portions with a first holding-wing and a second holding-wing; said 15 end-portions and holding-wings adapted to have seatings upon the sides of the vertical strip; each of said second holding wings having a flange adapted to have a seating upon the inner face of said vertical strip.
9. A T-shaped brace of sheet metal, comprising, in combination with the horizontal cross-strip and vertical side-strip of the frame; a rectangular back adapted to have a seating 20 upon one of the horizontal faces of the horizontal strip with its outer terminal in engagement with the inner face of the vertical strip; parallel sides integral with the back and adapted to have seatings upon the vertical faces of the horizontal strip; each of 25 the sides extended longitudinally and outwardly of the back to form end-portions with transverse, oppositely-disposed wings; said end-portions and wings adapted to engage the sides of said vertical strip.
10. A T-shaped brace of sheet metal, comprising, in combination with the horizontal cross-strip and vertical side-strip of the frame, a back adapted to have a seating 30 upon one of the horizontal faces of the hori-

zontal strip and having its outer terminal in engagement with the inner face of the vertical strip; parallel sides integral with the back adapted to have seatings upon the vertical faces and having integral longitudinal flanges for seatings upon the opposite horizontal face of the horizontal strip; each of the side portions extended longitudinally and outwardly of the outer terminal of the back to form end-portions with transverse, oppositely-disposed wings, said end-portions 40 and wings adapted to engage the sides of said vertical strip.

11. A T-shaped brace of sheet metal, comprising, in combination with the horizontal cross-strip and vertical side-strip of the frame, a back adapted to have a seating upon one of the horizontal faces of the horizontal strip and having its outer terminal in engagement with the inner face of the vertical strip; parallel sides integral with the back 55 to have seatings upon the vertical faces of the vertical faces of the horizontal strip; each of the sides extended longitudinally and outwardly of the outer terminal of the back to form end-portions with a first holding-wing and a second holding-wing; said end portions and holding-wings adapted to have seatings upon the sides of the vertical strip; each of said second holding wings having a flange adapted to have a seating 60 upon the inner face of said vertical strip.

In testimony whereof I have affixed my signature in presence of two witnesses.
